UNITED STATES PATENT OFFICE.

LOUIS H. FUELLING, OF NEW YORK, N. Y., ASSIGNOR TO THE UNITED STATES PRINTING AND LITHOGRAPH CO., OF BROOKLYN, NEW YORK, A CORPORATION OF OHIO.

ART OF MAKING EMBOSSED DESIGNS.

1,350,365.

Specification of Letters Patent. Patented Aug. 24, 1920.

No Drawing.

Application filed March 6, 1918. Serial No. 220,847.

To all whom it may concern:

Be it known that I, LOUIS H. FUELLING, a citizen of the United States, and a resident of the county of Kings, city and State of New York, have invented a certain new and useful Improvement in the Art of Making Embossed Designs, of which the following is a specification.

My invention relates to an improvement 10 in the art of making embossed designs, particularly such as simulate the natural texture and color of fabrics.

Heretofore such designs were obtained by a laborious and inaccurate method of etching a duplicate of the fabric. This required 15 the services of an etcher and made the process not only expensive but the texture would only be approximated in accordance with the skill of the etcher, and produced 20 at best only the general effect of fabric without creating any accurate or exact reproduction.

My invention not only results in great 25 accuracy of reproduction and in the resultant satisfying impression on the eye of the observer, but also enables me to dispense with the necessity of skilled help and to obviate the personal equation by making 30 entirely mechanical that which had heretofore been but indifferently accomplished by artisan hands.

My invention comprises the steps of rendering the fabric capable of retaining its natural physical form while being subjected 35 to pressure pressing the fabric itself into a thermoplastic mass, removing the fabric and using said impressed mass as a matrix, producing a positive from said matrix and transferring the positive by pressure to an 40 impressionable medium. In carrying out my invention, I treat as by immersion the fabric in a solution comprising silicate of soda, or its equivalent. I have found that a solution containing about one part by 45 weight of silicate of soda and three parts by weight of water makes a suitable material. The fabric is treated with this solution until the fibers are impregnated. This renders the fabric relatively rigid and pressure-resisting and causes it to keep its original and normal shape through the next 50 following operations. The thus hardened fabric is then rendered non-adhesive by being suitably surfaced, as for instance by

being dusted with plumbago. A sheet of 55 ebonite, or other suitable thermoplastic material is placed against the fabric after it has been treated as above specified, and the two suitably positioned are then heated and held together between steel plates, for example: When ebonite is used, a temperature of between 250° and 350° Fahrenheit is suitable, but obviously depends somewhat on the composition and size of the mass. The steel plates with the fabric and softened 60 ebonite are now placed in a hydraulic press and subjected to a pressure of 250 to 400 tons for a period of about three to five minutes, the pressure and time being regulated by the object to be obtained, to wit, 65 that the thermoplastic mass shall take an accurate impression of the surface irregularities and other physical characteristics relating to the form or shape of the fabric. The fabric is then separated from the thermoplastic mass, which latter, when it becomes hard, forms an accurate impression 70 or matrix of the fabric. A metallic die may now be made from the matrix by electroplating. The electro-plate thus obtained 75 may be used as a die to emboss the paper on which the reproductions are to appear.

The method above described may be very satisfactorily employed in obtaining replicas 80 of laces or similar fabrics which are replete in delicacy and detail of contour and form and could only be hand-engraved at prohibitive expense.

In order to obtain reproduction of the proper colors, the fabric is photographed 85 before being transferred to the thermoplastic mass. If the fabric is of a light color, as in laces, it is fastened upon a metal sheet of contrasting color, such as black ferotype, the fastening means being a suitable 90 colorless cement for which purpose the water-glass which is used as the impregnating medium may serve. If a plurality of fabric-similitudes are to be obtained on a single sheet, and such is frequently the case, 95 the samples of fabrics to be reproduced are first mounted as above described, and (as is also the case generally) suitable indicating marks placed on the mount to facilitate 100 the subsequent alinement of the printed colors and the die. The mount with the fabrics and indicating marks is then photographed, and the color printing prepared 105

in usual fashion and in such a way as to retain the indicating marks throughout. The fabrics, impregnated or sprayed with a solution as above described, are pressed 5 onto the thermoplastic mass, as described, and the indicating marks are carried along into the ultimate die. The similitude is then transferred to the paper the indicating marks being first made to register with 10 those derived in the photographic operation. This results in securing accurate relation between form and color and the final product is so exact and perfect as to resemble almost indistinguishably the original fabric. 15 Various modifications may be made in the proportions and steps hereinbefore described, the procedure being described merely as exemplifying my invention, and in nowise restricting it to the specific dis- 20 closure.

I claim:

1. The improvement in the art of making embossed designs which consists in mounting a piece of fabric in a fixed position on a 25 pressure resisting backing, rendering the fabric pressure resisting, making an impression from the stiffened fabric, while mounted, upon a softened plastic mass by applying relatively high pressure to the backing, 30 the fabric and the plastic mass, removing the fabric and its backing, causing the plastic mass to become rigid, preparing a die therefrom, preparing a photographic reproduction of the fabric as mounted upon 35 its backing at a time prior to the said pressure stage, printing an image thereof upon paper and impressing the die upon said paper in registry with the said print.

2. The improvement in the art of making 40 embossed designs which consists in mounting a piece of fabric in a fixed position on a pressure resisting backing, said backing being of contrasting color with that of the fabric, rendering the fabric pressure resist- 45 ing, making an impression from the stiffened fabric, while mounted, upon a softened plastic mass by applying relatively high pressure to the backing, the fabric and the plastic mass, removing the fabric and 50 its backing, causing the plastic mass to become rigid, preparing a die therefrom, pre-

paring photographic reproductions from the fabric as mounted on the backing, adapting said reproductions for color printing to reproduce the colors of the original 55 fabric, printing a colored image of said fabric upon paper and impressing the die upon said paper in registry with the said print.

3. The improvement in the art of making 60 embossed designs which consists in mounting a piece of fabric in a fixed position on a pressure resisting backing, rendering the fabric pressure resisting, rendering the surface of the fabric non-adhesive with respect 65 to the plastic mass subsequently employed, making an impression from the stiffened fabric, while mounted, upon a softened plastic mass by applying relatively high pressure to the backing, the fabric and the 70 plastic mass, removing the fabric and its backing, causing the plastic mass to become rigid, preparing a die therefrom, preparing a photographic reproduction of the fabric as mounted upon its backing at a time prior to 75 the said pressure stage, printing an image thereof upon paper and impressing the die upon said paper in registry with the said print.

4. The improvement in the art of making 80 embossed designs which consists in treating a piece of fabric with a solution comprising sodium silicate, mounting the said saturated fabric in a fixed position upon a pressure resisting backing, rendering the surface of 85 the fabric non-adhesive with respect to the plastic mass subsequently employed, making an impression from the stiffened fabric, while mounted, upon a softened plastic mass by applying relatively high pressure to the 90 backing, the fabric and the plastic mass, removing the fabric and its backing, causing the plastic mass to become rigid, preparing a die therefrom, preparing a photographic reproduction of the fabric as mounted upon its backing at a time prior to the 95 said pressure stage, printing an image thereof upon paper and impressing the die upon said paper in registry with the said print.

In witness whereof I have hereunto set 100 my hand this 23d day of January, 1918.

LOUIS H. FUELLING.
